AUTOMATIC RECEPTACLE LOCK

John Garthe, Northport, Mich., assignor of one-fourth to Edward H. Rude and one-fourth to Oscar M. Rude, Suttons Bay, Mich.

Application October 6, 1938, Serial No. 233,683

1 Claim. (Cl. 232—41.4)

This invention relates to a means adapted for the deposit of milk bottles and their retention against theft pending removal by the authorized person or owner.

It is further aimed to provide a structure in the nature of a receptacle having doors on opposite sides one of which doors may be locked after deposit of the milk bottle or other article and which will remain locked until released through operation of the other door, said latter door also being operable to unlatch the first mentioned door.

The more specific objects and advantages will become apparent from a consideration of the description following taken in connection with accompanying drawings illustrating an operative embodiment.

In said drawings:

Figure 1 is a view in front elevation showing my improvements installed in a wall;

Figure 2 is a cross sectional view taken on the line 2—2 of Figure 1;

Figure 3 is a vertical sectional view taken on the line 3—3 of Figure 1;

Figure 4 is a horizontal sectional view taken on the line 4—4 of Figure 3;

Figure 5 is a section taken on the same plane as Figure 4 but showing the interior door open;

Figure 6 is a cross section taken on the line 6—6 of Figure 3, and

Figure 7 is a cross section taken on the line 7—7 of Figure 3.

Referring specifically to the drawings wherein like reference characters designate like or similar parts, a receptacle is provided to receive milk bottles or any equivalent in a compartment 10, through a space covered by a doorway normally closed by a door 11 opening from the outside of a building, which milk bottles or the like are adapted to be removed from the interior of the building through a doorway or space normally closed by a door 12.

Said receptacle has a rectangular frame 13 which is built into a wall 14 of a building. Frames 15 and 16, on the outside and inside of the wall 14 surround the frame 13 and are fastened thereto. Outside door 11 is pivoted or hinged at 17 to the frame 15 and has a conventional latch mechanism at 18 to secure the door 11 against accidental opening to the frame 15. In a similar manner, the door 12 is hinged as at 19 to the frame 16 and a conventional latch 19 is employed to secure such door 12 to the frame 16 against accidental movement.

Fastened to one of the vertical walls of frame

13 in the space 10, as by means of screws 20, is a bar or plate 21 preferably having one end curved or deflected as at 22 and provided with a slot 23.

Slidable along the plate or bar 21 is an auxiliary bar 24, the same being guided in surrounding loops 25 and 26, struck out from and integral with the bar 21. A contractile coil spring 27 is fastened at one end to a lug 28 on the auxiliary bar 24 and at its other end to a lug 29 on 10, the loop 26. Such bar 24 when unrestrained, will be projected by the spring 27 into the path of closing of the door 12. Such door 12 preferably has a wear strip or plate at 30 adapted to directly abut the adjacent end of bar 24.

Door 11 on the interior thereof carries a latch member 31, pivoted at 32 to a bracket 33 suitably secured to door 11. Such latch 31 is urged to projected position by a spring member 34 interiorly of the latch, abutting the same at one end and abutting the bracket 33 at the other end. Said latch 31 has a point or hook 35 which will engage and snap into the opening 23 when the door 11 is closed.

In the operation of the device, the inside door 12 is left closed and the outside door 11 is also closed but with latch 31 held retracted from slot 23 by bar 24 as in Figures 1 and 2 or with such outside door 11 left open. The inside door does not have to remain closed, but closing movement 30 thereof is necessary to slide bar 24 from the position of Figure 5 to that of Figure 2. After the milk bottle or other article is deposited by the distributor within the compartment 10, door 11 is pushed inwardly and the latch 31 wedges 35 between the somewhat flexible blades or bars 21 and 24 and engages the slot 23 as shown in Figure 4. The latter figure shows the door 11 in an intermediate position during its closing movement. The door 11 cannot be opened from the exterior by an unauthorized person because of such engagement of latch 31 in slot 23. The authorized person from the interior of the building, may remove the deposited bottle or the like when door 12 is opened as in Figure 5. However, the latch 31 must be detached from the slot 23 before the door 11 can be again opened to receive another bottle or article. To this end, it is necessary to close the door 12 which will abut the projected end of the bar 24 in its path (see Figure 5), sliding the latter into engagement with the latch 31 and swinging the latch away from bar 24 against the tension of its expansive spring 34, and detaching it from the slot 23 as in Figure 2, whereupon the door 11 may thereafter

50

55

be opened upon the operation of the latch 17. It will be realized that the latch will automatically lock any time door 11 is closed because the latch 31 will travel along plate or bar 21, and by means of spring 34 will snap into the slot 23. To facilitate the engagement and disengagement, such bars 21 and 24 are somewhat flexible and yieldable at their forward end.

Various changes may be resorted to provided they fall within the spirit and scope of the invention.

I claim as my invention:

In a locking device having a bar provided with a slot for engagement by a latch carried by a

door, and a bar slidable relatively to the first bar controlled by another door; a spring urging the second bar into the path of movement of the second door, the second bar being of a length for pushing by closing of the second door to effect disengagement of the latch from said slot, the first mentioned bar having a curved portion in which said slot is provided, the other bar at the corresponding end having a portion which may be deflected away from said curved portion to enable the latch to enter between such portions to effect engagement with said slot.

JOHN GARTHE.
